UNITED STATES PATENT OFFICE.

THOMAS NATHAN RUSSELL, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

CAR END.

1,414,157.

Specification of Letters Patent. Patented Apr. 25, 1922.

Application filed February 21, 1921. Serial No. 448,545.

To all whom it may concern:

Be it known that I, THOMAS NATHAN RUSSELL, a citizen of the United States, residing in Chicago, in the county of Cook and State of Illinois, have invented a new and useful Improvement in Car Ends, of which the following is a specification.

The invention relates to the end structure of ventilated box cars, and has for an object 10 to attain thorough ventilation through the car end, with free egress of heated air and gas and ingress of fresh air, without diminishing the strength of the car end; and to attain such object by a simple and economical sheet metal construction, which, in forming the ventilating openings, strongly braces the car end, and also is susceptible of ready repair in case of damage.

With such objects in view as well as other 20 advantages which may be incident to the use of the improvements, the invention consists in the parts and combinations thereof hereinafter set forth and claimed, with the understanding that the several necessary elements constituting the same may be varied 25 in proportions and arrangement without departing from the nature and scope of the invention.

In order to make the invention more 30 clearly understood there are shown in the accompanying drawings means for carrying the same into practical effect, without limiting the improvements, in their useful applications, to the particular constructions 35 which, for the purpose of explanation, have been made the subject of illustration.

In the said drawings—

Fig. 1 is an end view of a ventilated box 40 car embodying the invention.

Fig. 2 is a plan view of the roof frame at the end of the car.

Fig. 3 is a vertical section of the car end on line 3—3 of Figure 1.

Fig. 4 is a vertical section on line 4—4 of 45 Figure 1.

Fig. 5 is a horizontal section on line 5—5 of Figure 1.

Fig. 6 is an end elevation of a modification 50 having the end sheets extended to the top of the car.

Fig. 7 is a section on line 7—7 of Figure 6.

Fig. 8 is a section on line 8—8 of Figure 6.

Fig. 9 is a plan view of roof frame at the 55 end of the car shown in Figure 6.

Referring to the drawings, 6 indicates the end sill of the car body frame, 7 the end posts, 8 the flooring, 9 the wooden end sheathing or lining, 10 the side sheathing, 11 the end plate of the roof frame, 12 the ridge pole, 13 the side plates, 14 the purlins, and 15 the top sheathing. These parts may be constructed in a usual manner suitable 60 for the invention.

The end wall of the car comprises two sheet metal plates or sections 17 which extend from the end sill 6 to the end plate 11 and are secured to those parts. These plates are spaced apart at the middle of the car 70 (Fig. 1) to leave a vertically extending opening, which, however, is partly closed by top, middle and bottom cross plates 19, 20 and 21 which are strongly attached to the inner edges of the plate sections 17 by bolts 75 or rivets 22. The upper ends of said sections are formed with inturned horizontal flanges 23 which support the end plate 11 and are secured thereto by bolts 24. The outer side edges of the sections 17 are formed with 80 vertical flanges 25 (Fig. 5) which enclose the side sheathing for a short distance and are secured to the posts 7 by bolts 26.

The said car end sections 17 are formed with vertical corrugations 27 which extend 85 inwardly from the plane of the plate, springing from flat and relatively narrow bases 28 and having inclined sides 29 which are or may be of greater width than said bases, as shown in Fig. 5. What may be termed the inner parts or apices 30 of said corrugations are flat and against them is laid the end sheathing or lining 9. At suitable intervals are arranged filler bars or posts 31, vertically arranged and extending from the end sill to the end plate, and engaging by their outer sides the corrugation-bases 28 and by their inner sides the said sheathing 9. At their upper and lower ends the corrugations 27 taper endwise and outwardly as seen at 32 95 and merge into the normal plane of the end sections 17 as seen in Figs. 1 and 4.

The cross elements 19, 20, 21 are formed with similar or equivalent stiffening corru-

gations as clearly shown in Figs. 1, 3 and 5. All of the corrugations described are or may be of the flattened or truncated form which is the subject in part of my Patent No. 5 1,332,857, granted March 2, 1920.

Referring to Fig. 1 it will be seen that the cross elements 19, 20 and 21 are arranged to form upper and lower ventilator openings 33 and 34 of the desired area. If these openings are desired to be smaller the sections 17 10 will be constructed to have their inner edges approach nearer to one another, and the cross elements may be correspondingly widened in vertical directions; and a narrowing 15 of either the vertical or cross elements would produce larger openings. These ventilator openings are adapted to receive any usual form of ventilator.

The top cross member 19 is formed with 20 an inwardly turned horizontal flange 41 which lies under the flange 23 (Fig. 3).

In Fig. 2 is shown a plan view comprising the end sections and cross elements, together with side bars 37 which extend along the 25 side plates, and which are connected by gusset plates 36 with the flanges 23 of the end sections. The end elements are also braced by diagonal bars 39 which will be connected with the bars 37 by suitable means 30 (not shown) and the other ends of which are connected by rivets 40 with the flanges 23 of the end sections and with the top flange 41 of the cross plate 19.

In the form shown in Figs. 6 to 9, the sheet 35 metal plates or sections 42 and top cross plate 43, are extended up and have their flat vertical top margins secured to the angle-bar end-plate 44 that supports the ridge-pole 45 and purlins 46 and is secured 40 at its ends to the angle-bar side-plates 47, in the manner shown in Fig. 9, the ends of the top leg of the said angle end-plate being cut away and the ends of its vertical leg being bent inward and riveted to the said side- 45 plates. The gusset plates 48 further secure this juncture of the side-plate and end-plate angle-bars at each corner of the car. The wood-filers 49 occupy the spaces between the ridge-pole and purlins, along the end-plate 50 and are bolted to the said end-plate.

What is claimed is—

1. In a ventilated box car, an end structure comprising vertically corrugated sheet metal end sections which are spaced apart at their 55 inner edges, and horizontally corrugated cross plates which are spaced apart one above the other and attached at their edges to the inner edges of said end sections, the whole structure forming ventilator openings 60 in the car end.

2. In a ventilated box car, an end structure comprising vertically corrugated sheet metal end sections which are spaced apart at their inner edges, and horizontally corrugated

cross plates which are spaced apart one 65 above the other and attached at their edges to the inner edges of said end sections, the whole structure forming ventilator openings in the car end, said corrugations extending inwardly from the outer plane of the 70 car end.

3. In a ventilated box car, an end structure comprising vertically corrugated sheet metal end sections which are spaced apart at their inner edges, and horizontally corrugated 75 cross plates which are spaced apart one above the other and attached at their edges to the inner edges of said end sections, the whole structure forming ventilator openings in the car end, said corrugations extending 80 inwardly from the outer plane of the car end and formed with flat outer faces and flat inner faces.

4. In a ventilated box car, an end structure comprising vertically corrugated sheet metal 85 end sections which are spaced apart at their inner edges, and horizontally corrugated cross plates which are spaced apart one above the other and attached at their edges to the inner edges of said end sections, the 90 whole structure forming ventilator openings in the car end, said corrugations extending inwardly from the outer plane of the car end and formed with flat outer faces and flat inner faces of less width than the width of 95 the inwardly extending parts of the corrugations.

5. In a ventilated box car, an end structure comprising vertical sheet metal end sections which are spaced apart, and formed with 100 vertical tapering corrugations; and cross plates, spaced apart, attached at their ends to said end sections and formed with horizontal tapering corrugations.

6. In a ventilated box car, an end structure 105 comprising vertical sheet metal end sections which are formed with vertical corrugations extending inwardly from the plane of said sections, said sections being spaced apart; and cross plates attached to said end sections 110 and closing the top and bottom and middle part of the space between said sections, and arranged to leave ventilator openings, said cross plates having horizontal tapering corrugations.

7. In a ventilated box car the combination of a roof frame, an end structure comprising vertically corrugated sheet metal end sections which are spaced apart at their inner edges, and horizontally corrugated cross 120 plates which are spaced apart one above the other and attached at their edges to the inner edges of said end sections, the whole structure forming ventilator openings in the car end, and side bars and diagonal bars 125 connected with the top edges of the end sections and with the roof frame.

THOMAS NATHAN RUSSELL.
